UNITED STATES PATENT OFFICE.

EDMUND O. JOHNSON, OF WARRENS, WISCONSIN.

HAT-STRETCHER.

1,187,741.

Specification of Letters Patent. Patented June 20, 1916.

Application filed February 21, 1916. Serial No. 79,699.

To all whom it may concern:

Be it known that I, EDMUND O. JOHNSON, a citizen of the United States, residing at Warrens, in the county of Monroe and State 5 of Wisconsin, have invented a new and useful Hat-Stretcher, of which the following is a specification.

The device forming the subject matter of this application is a hat stretcher embodying an expandible frame, and the invention 10 aims to provide novel means for operatively connecting the constituent parts of the frame, and to provide novel means for producing relative movement between the constituent parts of the frame, thereby to secure 15 expansion and contraction.

It is within the province of the disclosure to improve generally and to enhance the utility of devices of that type to which the 20 present invention appertains.

With the above and other objects in view which will appear as the description proceeds, the invention resides in the combination and arrangement of parts and in the 25 details of construction hereinafter described and claimed, it being understood that changes in the precise embodiment of the invention herein disclosed can be made within the scope of what is claimed, without departing from the spirit of the invention.

In the accompanying drawing:—Figure 1 shows in plan, a structure embodying the present invention, parts being broken away; Fig. 2 is a cross section on the line 2—2 of 35 Fig. 1; Fig. 3 is a fragmental longitudinal section showing the operative connection between the sides and the ends of the expandible frame of the stretcher.

The stretcher herein disclosed may be 40 fashioned from any desired material and embodies ends 1 and sides 2. The ends 1 are equipped with slots 3 disposed parallel to the upper and lower faces of the ends 1, the sides 2 carrying projecting pins 4 received in the slots 3. The slots 3 and the pins 4 constitute interengaging elements 45 coacting to hold the sides and the ends together for relative expanding and contracting movements in a common plane.

The invention comprises a screw including 50 a handle 5, intermediate portions 6 and terminal portions 7. The terminal portions 7 are threaded in opposite directions, the intermediate portions 6 are threaded in opposite directions, and each of the intermediate portions 6 is threaded in a direction opposite to

the adjoining terminal portion 7. The terminal portions 7 of the screw are threaded into the ends 1, the intermediate portions 6 of the screw being threaded into travelers 8 60 provided with ears 9. Ears 10 are mounted on the sides 2 of the expandible frame. Pivot elements 11 are mounted, respectively, in the ears 9 and 10 and support links 12 forming an operative connection between the travelers 8 and the sides 2.

The intermediate portions 6 of the screw are slightly larger in diameter than the terminal portions 7, so that the travelers 8 may be mounted readily in place. The 70 intermediate portions 6 are given more threads to the inch than are the terminal portions 7. As illustrating a convenient but not mandatory ratio, the intermediate portions 6 of the screw may be given twelve 75 threads to the inch, the terminal portions 7 of the screw being given eight threads to the inch.

When the screw is rotated by means of the handle 5 the ends 1 move toward or away 80 from each other, depending upon the direction in which the screw is rotated. The sides 2 likewise move toward or away from each other, under the action of the links 12 and the travelers 8 which move along the intermediate portions of the screw.

Having thus described the invention, what is claimed is:—

1. In a hat stretcher, an expandible frame comprising sides and ends; interengaging elements on the sides and the ends coacting to hold the sides and the ends together for relative expanding and contracting movements in a common plane; a screw comprising a handle, intermediate portions disposed on opposite sides of the handle and threaded in opposite directions, and terminal portions threaded in opposite directions, each of the terminal portions being threaded in a direction opposite to the adjusting intermediate portion, the terminal portions of the screw being threaded into the ends; travelers into which the intermediate portions of the screw are threaded; and links pivotally connecting the travelers with the sides. 95

2. In a hat stretcher, an expandible frame comprising sides and ends; a screw including a handle, intermediate portions disposed on opposite sides of the handle and threaded in opposite directions, and terminal portions threaded in opposite directions, each terminal portion being threaded in a direc- 105

tion opposite to the adjoining intermediate portion, the terminal portions of the screw being threaded into the ends; travelers into which the intermediate portions of the screw are threaded; and links pivotally connecting the travelers with the sides.

3. In a hat stretcher, an expandable frame comprising sides and ends; a screw including oppositely threaded end portions and a threaded intermediate portion, the terminal portions of the screw being threaded

into the ends; a traveler into which the intermediate portion of the screw is threaded; and links pivotally connecting the traveler with the sides.

In testimony that I claim the foregoing as my own, I have hereto affixed my signature in the presence of two witnesses.

EDMUND O. JOHNSON.
